13, 1928

27 Claims. (Cl. 123—32)

This invention relates to internal combustion oil engines which are provided with regulation means to determine the quantity of fuel oil to be injected for each working stroke. In such engines it has been already proposed, in order to promote the combustion, to decrease the supply of air upon a reduction of the supply of fuel for each working stroke by means of a damper or a similar valve inserted in the suction conduit 5 of the engine and mechanically connected to a regulating device of the fuel pump so that the damper has been caused to throttle the supply of air according as the fuel pump has been adjusted under the control of the regulating device 10 to deliver a reduced quantity of fuel oil at each such stroke. Such an arrangement, however, gives a very approximate and unreliable regulation of the supply of air. Particularly, said regulation does not take care of variations of the 15 number of revolutions of the engine, in as much as the area left open at the damper will be the same at high and low numbers of revolutions. As a result, the quantity of air supplied for each stroke of the pump plunger will be smaller at a 20 high number of revolutions than at a lower number of revolutions. When the engine works at a low load and a high number of revolutions it may thus happen that the supply of air will be so small as to give rise to a harmful or otherwise 25 non-desirable vacuum within the cylinder.

The present invention has for one of its principal objects the provision of means for maintaining a desired ratio between the quantity of air admitted and the quantity of fuel admitted for each working stroke of the engine throughout the normal working range of engine loads, and for maintaining such ratio at a substantially constant value, irrespective of the variations in engine speed at a given load, without 35 unduly restricting the admission of air under any circumstances of load on the engine. This is accomplished by providing a spring loaded valve responsive to variations in engine suction for restricting the admission of air to the engine, the spring load on which is increased or decreased 40 upon increase or decrease of the quantity of fuel supplied per working stroke within the lower load range of the engine, and by so constructing and arranging said valve means that within the upper load range of the engine the admission of air is not affected by the spring load.

Other and more detailed objects of the invention and the manner in which the several objects are attained will appear as the following 45 description of several suitable embodiments of

apparatus for carrying the invention into effect proceeds.

In the accompanying drawings forming a part of this specification:

Fig. 1 is a vertical section of an embodiment. 60 The invention is characterized, chiefly, by the fact that the air throttling device comprises a spring loaded valve the spring load of which is varied due to the adjustment of the fuel regulating device. Due to this spring load the air admission area left open by the valve at a certain adjustment of said regulating device will not be fixed but will depend on the number of revolutions of the engine so that the said area will be larger according as the number of revolutions 65 and thus also the action of the engine in drawing in air increases. For each adjustment of the fuel regulating device or the spring load there may thus be a larger or smaller air admission area left open by the valve according as the 70 number of revolutions is higher or lower, that is to say, a substantially constant ratio will be maintained between the quantity of air inducted for each working stroke of the engine and the quantity of fuel delivered for each such working 75 stroke.

In the accompanying drawings several embodiments of the invention are shown.

Fig. 1 is a vertical section of an embodiment of the invention, adapted for a vehicle engine. 80 Fig. 1a is a section on a larger scale of a part of the apparatus shown in Fig. 1. Fig. 2 is a section of a modified embodiment, likewise adapted for a vehicle engine. Figs. 3 and 4 are sections of an air regulating device especially adapted for a small engine which comprises a single spring loaded valve. Fig. 3 illustrates the position of the valve at full load, and Fig. 4 illustrates the position of the valve at low load. Figs. 5 and 6 are sections of an air regulating 85 device especially adapted for large engines which comprises a differential valve. Fig. 5 illustrates the position of the valve at low load and Fig. 6 illustrates the position of the valve at full load. 90

With reference to Fig. 1 the numeral 1 indicates the cylinder of an internal combustion engine driven by liquid fuel injected towards the end of the compression stroke. The injection is effected through the nozzle 2 supplied with fuel 105 from the pump 3. Combined with the fuel pump 3 is a mechanism to control the quantity to be injected, said mechanism comprising, as shown, a lever 5 engaging the pump plunger 4 to limit the suction stroke of the plunger, and a hand le- 110

ver 6 by means of which the lever may be manually operated, if desired. The suction stroke of the plunger 4 is effected, as shown, by a spring 7, whereas the discharge stroke is effected by a cam 5 8 through the intermedium of a sliding block 9.

The admission of air to the cylinder takes place through a channel 10 the connection of which with the cylinder is controlled by the valve 11. The connection between the channel 10 and the atmosphere is controlled by a regulating mechanism contained in a casing 12 communicating with the channel 10 and opened to the atmosphere at 13. The regulating mechanism shown comprises a slide valve 14, a spring controlled main valve 15 and a likewise spring controlled auxiliary valve 16. The slide 14 controls two rows of openings 17, 18 in the casing 12, the former by its upper edge and the latter by a series of openings 19 of little height as compared 20 with the height of the openings 17. The slide valve 14 is carried by the stem 20 carrying below the casing a spring 21 tending to maintain the slide valve in full open state. The lower end of the stem 20 rests on the lever 6 above referred to. 25 The stem 20 is extended above the slide valve 14 and supports by means of a light spring 22 a disc or plate 23 in turn supporting a heavier spring 24 acting on the valve 15. Said valve 15 controls a connection to the channel 10 by way of a branch channel 25 leading from the inlet 13. The valve 30 15 is adapted to be held out of action by being positively held in closed position when the engine runs at no load. To this end, I provide a pin 26 in alignment with the stem 20 and fitting in a sleeve 27, carried by said pin 26 and extending through the valve 15. The pin 26 with the sleeve 27 is longitudinally movable, and the sleeve 27 is provided at its lower end with a flange 28 adapted to engage the valve 15 and move it against 35 its seat when the pin 26 is moved upwards by the stem 20 in the upward movement of the slide valve 14, as will be hereinafter described.

The pin 26 may be longitudinally adjusted, in as much as it is screwed into a member 39 connected to sleeve 27. This is for the purpose of determining that position of the slide valve in which the valve 15 engages its seat, that is, the no-load position. Formed in the pin 26 is a by-pass channel 40 ending in the surface of the pin 50 below the flange 28. The area of the lower mouth of said channel may be adjusted by the above said adjustment of the pin 26. Said by-pass channel will allow a small quantity of air, which is the smaller the shorter the no-load stroke of the 55 plunger, to enter the passage 10 independently of the closed valve 15.

The connection between the branch channel 25 and the air passage 10 is also controlled by a valve 16 likewise operated by a spring the tension 60 of which is higher than that of the spring 24 acting on the valve 15 so that the valve 16 will be kept in closed state as long as the valve 15 is in operation.

In the embodiment above described the valve 65 15 is of annular shape, as shown. Due to this fact the valve may control large air admission ports in spite of its rather small area and, furthermore, a comparatively light spring may be used to act on the valve 15 with the result that the 70 operation of the hand lever 6 will be facilitated.

The operation of the mechanism described is as follows:

Normally, that is, when the engine works at normal or full load the air regulating mechanism 75 is in the position shown in Fig. 1. In this posi-

tion the air may enter freely through the openings 17, 18. At the beginning of the compression period there will thus exist, practically, atmospheric pressure within the cylinder. When the load sinks and the fuel pump regulating mechanism is, as a result, operated to reduce the quantity of fuel injected, by moving the control lever 6 upwards, the stem 20 with slide 14 will at the same time be lifted. This will effect a throttling of the admission of air first at a relatively slow rate, as long as the openings 19 are fully uncovered, and then at a successively higher rate. During the said last mentioned period of the slide movement a sleeve 29 secured to the stem 20 which carries the spring 22 will come into engagement with the lower surface of the disc 23 which will then constitute a rigid support for the spring 24 causing the latter to hold the valve 15 with a certain pressure against its seat. For the range of movement of the control lever 6 from full load position to that at which sleeve 29 engages the lower face of disc 23, which range corresponds to the upper load range of the engine, such regulation of the air inlet opening as is made is effected by the slide 14, the valve 15 being held 100 to its seat by spring load. Thus, in this range, the spring loaded valve does not control the admission of air. The valve 15 will come into action to assist to the regulation of the admission of air, that is, to allow more air to enter, as soon as the 105 throttling of the air in conformity with the load as effected by the slide valve 14 only allows such a little quantity of air to enter that the vacuum generated within the cylinder due, for instance, to an increase of the number of revolutions, will 110 allow the atmospheric pressure to open the valve 15 against the action of spring 24.

When the slide valve 14, due to reduction of the pump stroke, has been lifted to such a level as completely to cover the openings 17, 18, the 115 regulation of the air will be effected substantially entirely by the valve 15. According as the length of the pump stroke is further reduced, that is, the slide valve 14 is still further lifted the tension of the spring 24 will be increased and 120 the quantity of air passing through valve 15 correspondingly reduced so that it will keep substantially proportional to the quantity of fuel injected irrespective of the number of revolutions, inasmuch as the valve will open more at 125 higher number of revolutions than at lower. After the slide valve 14 has been lifted to such a level that the stem 20 has taken the pin 26 with it, causing the flange 28 to press the valve 15 against its seat, the valve 15 will be put out of 130 action.

The admission of air is now controlled by the above said by-pass channel 40 in the pin 26, by an adjustable no-load aperture 30, and by the valve 16 in conjunction. With the engine running slowly at no-load, as with the vehicles stationary, the quantity of air allowed to enter through 135 30 and 40 will give a sufficient pressure to insure combustion of all of the very small quantity of fuel injected at each stroke under these conditions, the number of revolutions being maintained constant or substantially constant by the fact that the reduction of pressure is in a very high degree dependent on the number of revolutions at constant inlet area. If, on the other 140 hand, the engine be running light at a high number of revolutions, as, for instance, with the car running down a hill, it may happen that the quantity of air as allowed to enter through 30 and 40 will be so little as to cause a high inner 145 150 pressure.

load, resulting in too high a braking effect and incomplete combustion of the fuel injected. In order to prevent this drawback the valve 16 is so arranged and its load so adjusted as to open 5 at a given vacuum suited to the circumstances in order thereby to limit the reduction of the pressure.

From the foregoing it will be seen that at intermediate engine loads the air admitted to the 10 engine is throttled under the influence of the spring load on valve 15, while at engine loads above such intermediate loads valve 15 is rendered ineffective as a throttling means even though it is closed due to the opening of the 15 ports uncovered by movement of valve 14. Similarly valve 15 is rendered ineffective under no-load operating conditions due to the by-pass provided to take care of such operation. It will further be noted that the valve 14 provides 20 through the opening of ports 17 and 18 for substantially unrestricted flow of air at full engine load or engine load which is substantially full load. As hereinafter employed the term "substantially full engine load" is intended to include what may be termed the full load range 25 of operation of the engine including not only actual full load, but also loads which approximate full load.

In certain cases the mechanism may be made 30 more simple by omitting the auxiliary valve 16, the no-load aperture 30 and the means to put the valve 15 out of action. Such a simplified regulating mechanism is shown in Fig. 2. The remaining parts are indicated by the reference 35 numerals as in Fig. 1 so that any detailed description is deemed unnecessary.

The embodiment shown in Figs. 3 and 4 is especially adapted for small engines. In this embodiment the air regulating mechanism comprises a spring operated valve only. Said valve 40 is shown as a valve plate 50 co-operating with a seat surrounding the air intake opening 51. The valve plate 50 may slide on the stem 52, which projects through the valve casing and is adapted 45 to be operated by the fuel pump control lever (not shown) in the same way as already described. The spring 53 acting on the valve plate 50 is supported by a disc 54 resting on a shoulder of the stem 52. Screwed on the end of the 50 stem 52 projecting above the valve plate 50 is a nut 55 serving as an upper valve stop in the way hereinafter described.

Fig. 3 illustrates the position of the regulating mechanism at full load on the engine. In this 55 position the nut 55 maintains the valve 50 in its lowermost position in which the largest quantity of air may pass through opening 51. In this position the spring 53 is not under tension or under a slight tension only. According as the amount 60 of fuel injected decreases the stem 52 will be lifted thereby successively bringing the valve plate 50 into engagement with its seat and, should the lifting movement of the stem continue, the spring 53 will be put under tension causing the valve 65 50 to begin its regulating action. When the pump stroke has been decreased as far as possible, that is, when the amount of fuel injected is equal to 0, the tension of the spring will balance the atmospheric pressure upon the valve plate thereby keeping the valve 50 in closed state.

As will be seen from Fig. 3, the annular opening between the valve seat and the valve 50, when the valve is in full load position, is so large with 70 respect to the area of the circular opening 51, that the initial upward movement of valve 50 from

full load position produces substantially the same effect as the slide 14 in the less simple valve arrangement of Fig. 1, particularly when spring 53 is under an initial tension. During the initial upward movement of valve 50, corresponding to the high load range of the engine, the spring load of spring 53 maintains valve 50 against the stop 55, and it is only when the valve 50 is moved sufficiently near to its seat to cause an appreciable vacuum to be formed in the intake pipe that the valve commences to function as a pressure responsive element. The range of adjustment of the control means in which a spring loaded valve acts as a pressure responsive element corresponds to the low load operating range of the engine.

Figs. 5 and 6 illustrate an embodiment of the invention which is especially adapted for large engines but may yet present certain advantages also in connection with small engines. In this embodiment the regulating means comprises two interconnected slide valve plates 60 and 61, respectively, of different diameter. The common stem 62 of said slide valve plates is acted on by a spring 63 the tension of which need only correspond to the air pressure acting on the difference of the valve areas. As a result, the power necessary to effect the regulation is small as compared with that required in the embodiments above described. At the same time, the air inlet areas with completely open valves are twice that of the embodiment shown in Figs. 3 and 4. As a further advantage it may be mentioned that the valve plates do not engage any seats but will enter the respective borings 64 and 65, when in closed state, as indicated by dotted lines in Fig. 105 5. In order to show the advantage of this arrangement it may be mentioned that the vacuum within the passage 10 is not constant especially in engines having but a few cylinders. This will cause the valves to oscillate. In the embodiments having valve seats the valves will consequently strike the seats—especially at low number of revolutions—which will result in a disturbing noise. In the embodiment shown in Figs. 5 and 6 the slide valve plates will oscillate about 110 a position of balance when the spring is under tension and throttling is to be effected. In Fig. 5 the spring is shown under slight tension while, in Fig. 6, the spring is not under tension and the air intake opening fully uncovered. This design 115 may, of course, be combined with auxiliary means similar to those shown in Fig. 1, that is stopping means to permit running at no-load, auxiliary valve, and no-load opening.

In the several embodiments illustrated it will 120 be evident that at substantially full engine load the air supply is unrestricted due to the fact that in the embodiment of Figs. 1 and 2 the ports controlled by slide 14 are fully uncovered, and that in the embodiments of Figs. 3-6 the spring loaded 125 valve member is moved away from its seat to a position providing full air inlet openings. It will further be evident that the several embodiments function to produce the same character of regulation, which provides variations of the area of 130 the air inlet opening in response to variations in engine suction in the low load range of engine operation, while providing an air inlet opening the area of which is determined only by the position 135 of the fuel regulating means in the high load range of engine operation.

While in compliance with the patent statutes, I have illustrated by way of example several suitable embodiments of apparatus for carrying the 140

invention into effect, it is to be understood that the invention is not limited in its scope to the precise forms of apparatus herein disclosed, but is intended to include all forms of apparatus falling within the scope of the appended claims when they are construed as broadly as is consistent with the state of the prior art.

What I claim is:

1. In an internal combustion engine, mechanism for supplying fuel to the engine, control means for governing the quantity of fuel delivered by said mechanism for each working stroke of the engine and means providing for the admission of combustion air to the engine, said last named means operating under the influence of said control means to provide substantially unrestricted flow of air to the engine at high engine loads and including a valve having a spring load variable under the influence of said control means for throttling the flow of air at lower engine loads subject to variations in the quantity of fuel delivered for each such working stroke. 80
2. In an internal combustion engine, mechanism for supplying fuel to the engine, control means for governing the quantity of fuel delivered by said mechanism for each working stroke of the engine and means providing for the admission of combustion air to the engine, said last named means comprising a valve movable independently of said control means upon variation in engine suction and having a spring load under the influence of said control means for throttling the flow of combustion air at intermediate engine loads subject to variations in the quantity of fuel delivered for each working stroke and means for rendering said valve ineffective to throttle the flow of air at engine loads above said intermediate loads. 85
3. In an internal combustion engine, mechanism for supplying fuel to the engine, control means for governing the quantity of fuel delivered by said mechanism for each working stroke of the engine and means providing for the admission of combustion air to the engine, said last named means comprising a valve having a spring load under the influence of said control means for throttling the flow of combustion air at intermediate engine loads subject to variations in the quantity of fuel delivered for each working stroke and means for rendering said valve ineffective to throttle the flow of air at engine loads above and below said intermediate loads. 90
4. In an internal combustion engine, mechanism for supplying fuel to the engine, control means for governing the quantity of fuel delivered by said mechanism for each working stroke of the engine and means providing for the admission of combustion air to the engine, said last named means comprising a valve having a spring load under the influence of said control means for throttling the flow of combustion air at intermediate engine loads subject to variations in the quantity of fuel delivered for each such working stroke, a second valve permitting substantially unrestricted flow of air at loads above said intermediate loads and a by-pass for admitting air at loads below said intermediate loads when said first mentioned valve is closed by said spring load. 95
5. In an internal combustion engine, mechanism for supplying fuel to the engine, control means for governing the quantity of fuel delivered by said mechanism for each working stroke of the engine and means providing for the admission of combustion air to the engine, said last named
- means comprising a valve movable independently of said control means upon variation in engine suction and having a spring load under the influence of said control means for throttling the flow of combustion air subject to variations in the quantity of fuel delivered for each such working stroke and means for rendering said valve ineffective to throttle the flow of air at substantially full engine load, whereby substantially unrestricted flow of air is secured at such load. 100
6. In an internal combustion engine, mechanism for supplying fuel to the engine, control means for governing the quantity of fuel delivered by said mechanism for each working stroke of the engine and mechanism for governing the admission of combustion air to the engine comprising a valve having a spring load under the influence of said control means for throttling flow of combustion air subject to variations in the quantity of fuel delivered for each working stroke and means for rendering said valve ineffective at substantially full engine load, said last named means comprising an air port and a second valve under the influence of said control means for opening said port when the control means is moved to substantially full load position. 105
7. In an internal combustion engine, mechanism for supplying fuel to the engine, control means for governing the quantity of fuel delivered by said mechanism for each working stroke of the engine and mechanism for governing the admission of combustion air to the engine comprising a valve movable independently of said control means upon variation in engine suction and having a spring load under the influence of said control means for throttling flow of combustion air subject to variations in the quantity of fuel delivered for each working stroke and means for rendering said valve ineffective at substantially full engine load, said last named means causing said valve to move to open position when said control means is moved to substantially full load position. 110
8. In an internal combustion engine, mechanism for supplying fuel to the engine, control means for regulating the quantity of fuel delivered by said mechanism for each working stroke of the engine and means for controlling the air supplied to the engine comprising a valve adapted to open due to differential air pressure caused by engine suction and a spring influenced by movement of the control means for applying to said valve a closing pressure increasing as the fuel supply is decreased, said valve being adapted to move to fully open position without resistance from said spring when the control means is moved to substantially full load position. 115
9. In an internal combustion engine, mechanism for supplying fuel to the engine, control means for regulating the quantity of fuel delivered by said mechanism for each working stroke of the engine and means for controlling the air supplied to the engine comprising a valve adapted to open due to differential air pressure caused by engine suction and a spring influenced by movement of the control means for applying to said valve a closing pressure increasing as the fuel supply is decreased, said spring being adjusted to exert a pressure substantially equal to atmospheric pressure when the control means is adjusted to deliver no fuel and said valve being adapted to move to fully open position without resistance from said spring when the control means is moved to substantially full load position. 120

10. In an internal combustion engine, mechanism for supplying fuel to the engine, control means for regulating the quantity of fuel delivered by said mechanism for each working stroke of the engine and means for controlling the air supplied to the engine comprising a valve adapted to open due to differential air pressure caused by engine suction and a spring influenced by movement of the control means for applying to said valve, a closing pressure increasing as the fuel supply is decreased, said spring being adjusted to exert substantially no pressure when the control means is adjusted to deliver relatively large quantities of fuel and to exert a pressure substantially equal to atmospheric pressure when the control means is adjusted to deliver no fuel and said valve being adapted to move to fully open position without resistance from said spring when the control means is moved to substantially full load position. 80
11. In an internal combustion engine, mechanism for supplying fuel to the engine, control means for governing the quantity of fuel delivered by said mechanism for each working stroke of the engine, a passage having an inlet for supplying combustion air to the engine, a plate valve for controlling said inlet, a spring load acting on said valve under the influence of said control means for maintaining a substantially constant ratio between the quantity of air and the quantity of fuel supplied for each such working stroke irrespective of variations in engine speed and a second air inlet for admitting air to said passage independently of the spring loaded valve. 90
12. In an internal combustion engine, mechanism for supplying fuel to the engine, control means for regulating the quantity of fuel delivered by said mechanism for each working stroke of the engine and means for controlling the air supplied to the engine comprising a substantially balanced double plate valve adapted to open due to differential air pressure caused by engine suction and a spring influenced by movement of the control means for applying to said valve a closing pressure increasing as the fuel supply is decreased, said valve being adapted to move to fully open position without resistance from said spring when the control means is moved to substantially full load position. 100
13. In an internal combustion engine, mechanism for supplying fuel to the engine, control means for regulating the quantity of fuel delivered by said mechanism for each working stroke of the engine and means for controlling the air supplied to the engine comprising an annular plate valve adapted to open due to differential air pressure caused by engine suction, a spring influenced by movement of the control means for applying to said valve a closing pressure increasing as the fuel supply is decreased and means influenced by movement of the control means for rendering said valve ineffective to throttle the flow of air at substantially full engine load. 110
14. In an internal combustion oil engine the combination of a fuel pump, a regulating device to determine the quantity of fuel to be delivered by said pump for each ignition, an air supplying passage, a slide valve to control the air supply under the control of said regulating device when adjusted to cause the pump to deliver large quantities of fuel oil for each ignition, a spring-loaded valve the spring load of which is under the control of said regulating device, said valve being adapted to be opened by the vacuum produced in the engine when the fuel regulating device is adjusted to cause the pump to deliver small quantities of fuel for each ignition. 120
15. In an internal combustion engine the combination of a fuel pump, a regulating device to determine the quantity of fuel to be delivered by said pump for each ignition, an air supplying passage, a slide valve to control the supply of air through said passage under the control of said regulating device when adjusted to cause the pump to deliver small quantities of fuel, and means controlled by said slide valve to maintain said spring-loaded valve in closed state when said regulating device is in the position corresponding to no load on the engine. 130
16. In an internal combustion oil engine the combination of a regulating device to determine the quantity of fuel oil to be delivered for each ignition, an air supplying passage, a valve to control the supply of air through said passage, a spring load acting on said valve under the control of said regulating device to keep the quantity of air supplied for each ignition substantially proportional to the quantity of fuel oil supplied for each ignition irrespective of variations of the number of revolutions of the engine, and a spring-loaded auxiliary valve to supply an additional quantity of air when the engine is running at low load at a high number of revolutions. 140
17. In an internal combustion engine, mechanism for supplying fuel to the engine, control means for governing the quantity of fuel delivered by said mechanism for each working stroke of the engine, a passage having an inlet for supplying combustion air to the engine, a valve for controlling said inlet, a spring load acting on said valve under the influence of said control means for maintaining a substantially constant ratio between the quantity of air and the quantity of fuel supplied for each working stroke irrespective of variations in engine speed, and means whereby a substantially unrestricted supply of air is admitted to said passage independently of the spring load on said valve when said mechanism is adjusted for substantially full engine load. 150
18. In an internal combustion engine, mechanism for supplying fuel to the engine, control means for governing the quantity of fuel delivered by said mechanism for each working stroke of the engine, a passage having an inlet for supplying combustion air to the engine, a valve for controlling said inlet and a spring load acting on said valve under the influence of said control means for maintaining a substantially constant ratio between the quantity of air and the quantity of fuel supplied for each working stroke irrespective of variations in engine speed, said spring load being provided by two springs of different strength, the value of the spring load being determined by the weaker of the two springs when said control means is adjusted for relatively high engine loads and the value of the spring load being determined by the stronger of the two springs when the control means is adjusted for relatively low engine loads. 160
19. In an internal combustion engine, mechanism for supplying fuel to the engine, control means for regulating the quantity of fuel delivered by said mechanism for each working stroke of the engine and means for controlling the air supplied to the engine comprising a valve 170

- adapted to open due to differential air pressure caused by engine suction, a spring for applying a closing pressure to said valve, an abutment for said spring movable in response to movements of said control means, said valve being movable with respect to said abutment and said spring being between the valve and the abutment, and adjustment means for varying the initial pressure exerted on the valve by said spring.

20. In an internal combustion engine having a working cylinder and an inlet for supplying combustion air to the cylinder, pump means for supplying a measured quantity of fuel to the cylinder for each working stroke, a valve for controlling said inlet, said valve comprising a valve member adapted to open under the influence of pressure of air admitted through said inlet and a spring load for closing the valve, said valve providing an inlet opening for flow of air increasing in size substantially direct proportion with movement of said valve member from closed position, regulating mechanism for regulating said pump means and said valve comprising parts operatively connected to move in substantially directly proportional relationship with respect to each other, the position of one of said parts determining the quantity of fuel delivered by said pump means for each working stroke and the position of the other of said parts determining the value of the spring load on said valve member resisting opening of the valve and means for rendering said valve member ineffective to control flow of air to said cylinder when said regulating mechanism is adjusted to provide a fuel supply suitable for substantially full load operation of the engine.

21. In an internal combustion engine having a working cylinder and an inlet for supplying combustion air to the cylinder, pump means for supplying a measured quantity of fuel to the cylinder for each working stroke, a valve for controlling said inlet, said valve comprising a reciprocable valve member adapted to open under the influence of pressure of air admitted through said inlet and a spring load for closing the valve, mechanism for regulating said pump means and said valve comprising parts operatively connected to move in substantially directly proportional relationship with respect to each other, the position of one of said parts determining the quantity of fuel delivered by said pump means for each working stroke and the position of the other of said parts determining the value of the spring load on said valve member resisting opening of the valve and means for rendering said valve member ineffective to control flow of air to said cylinder when said regulating mechanism is adjusted to provide a fuel supply suitable for substantially full load operation of the engine.

22. In an internal combustion engine having a working cylinder and an inlet for supplying combustion air to the cylinder, pump means for supplying a measured quantity of fuel to the cylinder for each working stroke, a valve for controlling said inlet, said valve comprising a reciprocable valve member adapted to open under the influence of pressure of air admitted through said inlet and a spring load for closing the valve, said valve member and said inlet cooperating to provide an inlet opening for flow of air increasing in size in substantially direct proportion with movement of the valve member away from closed position, regulating mechanism for regulating said pump means and said valve comprising parts operatively connected to move in substantially directly proportional relationship with respect to each other, the position of one of said parts determining the quantity of fuel delivered by said pump means for each working stroke and the position of the other of said parts determining the value of the spring load on said valve member resisting opening of the valve and means for rendering said valve member ineffective to control flow of air to said cylinder when said regulating mechanism is adjusted to provide a fuel supply suitable for substantially full load operation of the engine.

23. In an internal combustion engine having a working cylinder and an inlet for supplying combustion air to the cylinder, pump means for supplying a measured quantity of fuel to the cylinder for each working stroke, a valve for controlling said inlet, said valve comprising a reciprocable valve member adapted to open under the influence of pressure of air admitted through said inlet, a loading spring and an abutment against which said spring reacts, said spring tending to close said valve and said abutment being adjustable with respect to said inlet opening to determine the force required to open the valve against the resistance provided by the loading spring, regulating mechanism for regulating said pump means and said valve comprising parts operatively connected to move in substantially directly proportional relationship with respect to each other, the position of one of said parts determining the quantity of fuel delivered by said pump means for each working stroke and the position of the other of said parts determining the position of adjustment of said abutment relative to said inlet opening, said other of said parts determining a position of adjustment of said abutment for causing said valve member to be fully open when said regulating mechanism is adjusted to provide a fuel supply suitable for substantially full load operation of the engine.

24. In an internal combustion engine having a working cylinder and an inlet for supplying combustion air to the cylinder, a plunger pump for supplying a measured quantity of fuel to the cylinder for each working stroke, a valve for controlling said inlet, said valve comprising a reciprocable valve member adapted to open under the influence of pressure of air admitted through said inlet, said valve providing an inlet opening for flow of air increasing in size in substantially direct proportion with movement of said valve member from closed position, mechanism for regulating said pump means and said valve comprising a first part movable to alter the effective stroke of said pump whereby to regulate the quantity of fuel delivered by the pump for each working stroke and a second part operatively connected with said first part so as to move in substantially directly proportional relationship therewith, said second part providing an abutment and a loading spring for said valve, said spring reacting against said abutment and tending to close the valve, said second part having a position rendering said loading spring ineffective to move said valve member from fully open position when said regulating mechanism is adjusted to provide a fuel supply suitable for substantially full load operation of the engine.

25. In an internal combustion engine of the injection type, a pump for supplying fuel to the engine, control means for governing the quantity of fuel delivered by said pump for each working stroke of the engine, and valve means operatively

- associated with said control means for admitting air to the engine, said valve means including a valve part adapted to be opened by pressure of air admitted to the engine against a spring load the value of which is dependent upon the position of adjustment of the control means in the range of movement of the control means corresponding to the low load range of the engine and a part movable with said control means for controlling the admission of air independently of said spring load in the range of movement of the control means corresponding to the high load range of the engine, the last mentioned part being arranged to provide for substantially unrestricted admission of air when the control means is in a position of adjustment corresponding to substantially full load on the engine. 80
- 10 27. In an internal combustion engine of the injection type, a pump for supplying fuel to the engine, control means for governing the quantity of fuel delivered by said pump for each working stroke of the engine, and a spring loaded valve operatively associated with said control means for admitting air to the engine, said valve being movable with said control means independently of said spring load in the range of movement of said control means corresponding to the high load range of the engine and being movable relative to said control means under the influence of the pressure of air admitted to the engine and the said spring load in the range of movement of said control means corresponding to the low load range of the engine, said control means and said valve being arranged to permit the valve to move to a position permitting substantially unrestricted flow of air therethrough when the control means is moved to a position of adjustment corresponding to substantially full load on the engine. 85
- 15 26. In an internal combustion engine of the injection type, a pump for supplying fuel to the engine, control means for governing the quantity of fuel delivered by said pump for each working stroke of the engine, and valve means operatively associated with said control means for admitting air to the engine, said valve means comprising a valve member adapted to be opened by pressure of air admitted to the engine and having a spring load for closing the valve the value of which is influenced by the position of adjustment of the control means, said valve member being movable with respect to said control means under the influence of the pressure of said air and the said spring load in the range of movement of the control means corresponding to the low load 90

KNUT JONAS ELIAS HESSELMAN.

CERTIFICATE OF CORRECTION.

Patent No. 1,968,831.

August 7, 1934.

KNUT JONAS ELIAS HESSELMAN.

It is hereby certified that error appears in the printed specification of the above numbered patent requiring correction as follows: Page 1, line 60, commencing with "Fig. 1" strike out all to and including the word "shown" in line 83; and that the said Letters Patent should be read with this correction therein that the same may conform to the record of the case in the Patent Office.

Signed and sealed this 11th day of September, A. D. 1934.

Leslie Frazer

Acting Commissioner of Patents.
